UNITED STATES PATENT OFFICE.

CHARLES W. HALSEY, OF EVANSVILLE, INDIANA.

ICE-PICK.

SPECIFICATION forming part of Letters Patent No. 787,509, dated April 18, 1905.

Application filed June 2, 1904. Serial No. 210,900.

To all whom it may concern:

Be it known that I, CHARLES W. HALSEY, a citizen of the United States, residing at Evansville, county of Vanderburg, and State of Indiana, have invented certain new and useful Improvements in Ice-Picks, of which the following is a specification.

This invention relates to ice-picks.

My object is to provide an ice-pick which is simple, strong and durable, and inexpensive of manufacture, which will have improved provision for holding the points and permit removal of said points and replacement by others, if desired.

In carrying out the invention I provide an ice-pick wherein the body portion is formed of duplicate stampings or castings of steel or other suitable metal having portions forming sockets for the points and means for holding the points and for securing a handle to the body and hollow ribs, the details of construction of which will appear more fully herein-after, while the novel features are recited in the appended claim.

In the accompanying drawings, Figure 1 is a view of the complete ice-pick; Fig. 2, a view showing one of the halves of the body laid back to expose the interior and showing by dotted lines how the points lie in the sockets; Fig. 3, an end view with the points removed; Fig. 4, an edge view; Fig. 5, a sectional detail view illustrating how the sockets may be tapered to hold the points, and Figs. 6 and 7 detail views illustrating different forms the points and sockets may assume.

Referring first to Figs. 1, 2, 3, and 4, the body of the device is formed of duplicate halves 1 and 2, which may be stamped or cast from steel or other suitable metal and formed with the half-round sockets 3, which extend inwardly from the straight edge 4 at the end of the body, the half-sockets on the respective parts 1 and 2 forming complete cylindrical sockets open at their outer ends and closed at their inner ends by the end wall 5. For purposes of strength without appreciable addition of weight the halves 1 and 2 may be formed with hollow beads or ribs 6 and 7, which together form a tubular extension of

the end sockets and curve backwardly toward 50 the handle portion 8 of the body, where a shoulder 9 is formed and beyond which extends a hollow shank or tang 10, over which a suitable handle 11 may be secured. The braces 6 and 7 give great strength to the device, and to provide abutments corresponding to the walls 5 at the back of the end sockets 3 the shoulders or protuberances 12 are formed, which project toward each other across the end sockets in line with the end walls 5 of 60 the various sockets 3. The pick-points 13 have round shanks, which are received in the sockets 3, and the diameter of these pick-points is a trifle greater than the internal diameter of the sockets 3, so that said points 65 will be firmly clamped to the body by the use of the rivets or screws 14, which pass through the body intermediate the various sockets and also outside the end sockets. These fastenings 14 may either be rivets or screws, and I 70 sometimes find it preferable to use screws in order that the points may be readily removed at any time for replacement by others, and I do not wish to limit myself to either the use of rivets or screws.

As illustrated in Fig. 5, the shanks of the picks may be made tapering, as shown at 15, and the sockets 3 are correspondingly tapered. The greatest width of diameter of the sockets is at the walls 5 and diminishes toward the 80 mouths of the sockets. This construction prevents the picks from falling out; but with ordinary usage the plain cylindrical construction fills all requirements.

As shown in Figs. 6 and 7, the shanks of 85 the picks may be made oval or rectangular; but these constructions are not as desirable as those heretofore set forth.

The shoulder 9 is not absolutely essential, and obviously a separate handle 11 need not 90 necessarily be used, as the body of the device could be formed with an integral handle; if preferred.

The peculiar formation of the sockets and ribs permits the use of the same thickness of 95 metal throughout the body, thus cheapening the cost and lessening the weight of the tool, while also giving it great strength, and the

formation of the body in duplicate parts does away with extra operations in process of manufacture.

As contradistinguished from ordinary ice-picks the present ice-pick will chip ice into small particles.

Various changes of construction might be resorted to in carrying out the invention, such as will suggest themselves to the artisan skilled in this particular class of invention, and I do not limit myself to details of construction, except as stated in the claim.

Having thus described my invention, what I claim as new, and desire to secure by Letters Patent, is—

An ice-pick having a body composed of duplicate parts having alternating flat portions and substantially parallel matching half-sock-

ets whose backs constitute ridges on the exterior of the body and which extend inwardly from an edge of the body, and terminate in abutments for the pick-points, said body being also provided with converging matching hollow half ribs or braces whose backs constitute ridges on the exterior of the body and which join and continue as a single hollow handle composed of matching half-sections, pick-points in the sockets aforesaid, and fastenings connecting the two parts of the body together.

In testimony whereof I hereunto affix my signature in presence of two witnesses.

CHARLES W. HALSEY.
